[57] CLAIM

I claim the ornamental design for golf club head, as shown.

DESCRIPTION

FIG. 1 is a front elevational view of a golf club head showing a third embodiment of my design.

FIG. 2 is a top plan view thereof.

FIG. 3 is a rear elevational view thereof.

FIG. 4 is a bottom plan view thereof.

FIG. 5 is an end view of one of the mirror image opposing ends thereof; and,

FIG. 6 is a rear perspective view thereof.
